UNITED STATES PATENT OFFICE

102,808

DESIGN FOR A PAPER PLATE

William R. Van Winkle and Roland E. Pavey,
Marion, Ind., assignors to Indiana Fibre Products
Company, Marion, Ind., a corporation

Application November 14, 1936, Serial No. 65,917

Term of patent 7 years

To all whom it may concern:

Be it known that we, William R. Van Winkle and Roland E. Pavey, citizens of the United States and residents of Marion, county of Grant, and State of Indiana, have invented a new, original, and ornamental Design for a Paper Plate, of which the following is a specification, reference being had to the accompanying drawing, forming part thereof.

In the drawing, Fig. 1 is a top plan view of a

paper plate, showing our new design; and Fig. 2 is a transverse sectional view taken on the broken line 2—2 of Fig. 1 and in the direction of the arrows.

We claim:

The ornamental design for a paper plate, as shown.

WILLIAM R. VAN WINKLE.
ROLAND E. PAVEY.
